CLAIM

The ornamental design for a portion of a vehicle component having an icon, as shown and described.

DESCRIPTION

FIG. 1 is a front view of an embodiment of our design showing a portion of a vehicle component having an icon; FIG. 2 is a front view of an embodiment of our design showing a portion of a vehicle component having an icon; FIG. 3 is a front view of an embodiment of our design showing a portion of a vehicle component having an icon; and,

FIG. 4 is a front view of an embodiment of our design showing a portion of a vehicle component having an icon. The broken lines shown in the drawings indicate the boundary of an example portion of the vehicle component and form no part of the invention.
